United States Patent Office

Des. 220,657
Patented May 4, 1971

220,657

REAR PROJECTION VIEWER

William K. Christoffersen, North Minneapolis, James L. Keely, Wayzata, and William T. Owens, Jr., Long Lake, Minn., assignors to Washington Scientific Industries, Inc., Long Lake, Minn.

Filed May 21, 1970, Ser. No. 23,075

Term of patent 14 years

Int. Cl. D16—04

U.S. Cl. D61—1

FIG 1

FIG 2

FIG 3

FIG. 4

FIG. 5

FIG. 6

FIG. 1 is a front side perspective view of a rear projection viewer, showing our new design;

FIG. 2 is a front elevational view thereof;

FIG. 3 is a right side elevational view thereof;

FIG. 4 is a left side elevational view thereof;

FIG. 5 is a top elevational view thereof; and

FIG. 6 is a back elevational view thereof.

We claim:

The ornamental design for a rear projection viewer, as shown.
